UNITED STATES PATENT OFFICE.

NELS LARSEN, OF ST. PAUL, MINNESOTA, ASSIGNOR OF ONE-HALF TO
A. N. GRANTZ, OF ST. PAUL, MINNESOTA.

FIRE-ESCAPE.

SPECIFICATION forming part of Letters Patent No. 755,501, dated March 22, 1904.

Application filed August 30, 1902. Serial No. 121,650. (No model.)

To all whom it may concern:

Be it known that I, NELS LARSEN, a citizen of the United States, residing at St. Paul, in the county of Ramsey and State of Minnesota, 5 have invented a new and useful Fire-Escape, of which the following is a specification.

My invention relates to fire-escapes, and especially to that class of devices whereby the user is lowered to the street by means of a 10 belt and cable; and the object of my invention is to produce a device which will be ready for use at a moment's notice, which will not require any special skill in manipulating, and in which the speed of the cable can be regulated 15 by the person descending, by some one on the street, or by a person remaining at the window adjacent which the escape may be attached.

The construction of my device is fully illustrated in the accompanying drawings, in 20 which—

Figure 1 is a perspective view of my fire-escape, showing the brake-line dropped to the ground and the belt at the end of the cable. Fig. 2 is a perspective view looking toward 25 the right in Fig. 1 and showing position of the parts when not in use. Fig. 3 is a side elevation, partly broken away. Fig. 4 is a sectional view taken through the brake-shoe, and Figs. 5, 6, 7 are detail views of the brake-shoe.

30 In carrying out my invention I employ a substantially U-shaped frame A, adapted to be secured to or built in the wall of a house and having suitable braces A' and a vertical bar A², the purpose of which will be hereinafter 35 described.

As any suitable frame to support my mechanism can be used, it is not deemed necessary to describe that shown in detail. Journalized 40 in suitable boxings B, carried by the frame, is a shaft B', which carries a drum B², around which is coiled a cable of fireproof rope B³ or a chain, if preferred. At one end this shaft projects beyond the boxing and carries a pinion B⁴, adapted to mesh with a removable gear- 45 wheel B⁵, carried by a stub-shaft B⁶ and turned by a handle B⁷, this wheel being shown in operating position in dotted lines in Fig. 2.

The rear member of the frame A carries a

block C, having upwardly-projecting lugs C', between which are pivotally secured the 50 brake-bar C⁸, bearing on the roughened flange B⁹ of the drum. Mounted on this bar is a box C¹⁰, which serves as a receptacle for storing certain parts to be described hereinafter. Positioned in this box is a stub-shaft C¹¹, on which 55 the gear-wheel B⁵ is slipped when not in use.

Positioned on the rear of the frame and supported by a bracket, one member of which is shown at D, Fig. 3, is the reel D', carrying a brake-line D², which is coiled around the reel, 60 the free end being secured to the outer end of the brake-bar C⁸, as shown at D³, where it is illustrated as being perforated and the line passed through it and knotted at the end.

On the box B on the side opposite the brake-bar is a block E, having upwardly-extending lugs E'. Between these lugs rises a threaded rod E²². A block E³, perforated at E⁴, works on this rod and slides vertically between the lugs. On the inner side of this block and integral with it is the brake-shoe E⁵, which projects over the flange D⁹, which, like the flange B⁹, is roughened in order that the brake-shoe 70 may have a firmer grip.

The under surface of the brake-shoe is contoured, so that it will encircle the flange for some distance and insure a sufficient braking-surface. A handle E⁶, somewhat in the form of a thumb-screw and having an enlarged 75 perforated and threaded central portion, fits on the rod over the block and serves to regulate the tension of the brake-shoe. These parts are all shown in detail in Figs. 5, 6, and 7 and are shown assembled in Fig. 4.

Secured to the front end of the cable B³ is 80 the belt F, carrying hook members F' at one end and two parallel rows of eyes F², adapted to engage the hook members.

When not in use, the device may be covered by any suitable means, and with the exception of the belt, cable, and brake bar and shoe the device is preferably formed of metal, the brake bar and shoe being of wood.

The operation of my device is as follows: The person using the escape fastens the belt 95 under the arms and, having first lifted the

reel carrying the brake-line from its bracket and dropped it to the ground, steps on the frame and lowers himself over, holding the brake-line with one hand and to the bar A² 5 with the other, then permitting his weight to come as much as possible or necessary on the brake-line commences the descent, the cable unrolling as rapidly as permitted by the brakes. Should there be any one on the 10 ground below, they may regulate the brake-bar by means of the line, or should there be another person left at the window they may regulate the speed of the drum by the brake-shoe E³. It will thus be seen that the mech- 15 anism may be regulated by the brakes from three points—viz., by the person descending, from the ground, and from the window. For example, should there be children to be lowered and no one be on the ground below 20 the speed could be regulated from the window by the brake-shoe independently of the brake-bar.

Where more than one person is to descend, the cable may be wound up for a second use 25 by placing the gear-wheel B⁵ on the shaft B⁶.

It is obvious that the shape of the various parts comprising my device may be changed without departing from the spirit of my invention.

30 Having thus fully described my invention,

what I claim as new, and desire to secure by Letters Patent of the United States, is—

1. A device of the kind described comprising a drum, a cable thereon, a recessed block arranged adjacent the drum, a threaded rod 35 in the recess, a brake-shoe having a reduced portion resting in the recess and a curved portion extending over the drum, and a handle having a threaded bore working on the rod, and adapted to regulate the pressure of the 40 shoe on the drum.

2. A fire-escape comprising a frame, boxings carried by the frame, a shaft carrying a flanged drum said shaft being journaled in the boxings, a block arranged on one of the boxes 45 said block having upwardly-extending lugs, a vertical, threaded rod arranged between said lugs, a block adapted to slide on the rod between the lugs, a brake-shoe carried by the 50 slideable block and adapted to engage the periphery of the flange, and a handle having a centrally-arranged, threaded perforation, said handle being adapted to work on the threaded rod and force the brake-shoe into engagement with the flange.

NELS LARSEN.
